RADAR REFLECTOR

Roy Frank Williamson and Francis James Maurice Milner, London, England, assignors to A. C. Cossor Limited, London, England, a British company

Filed Apr. 24, 1961, Ser. No. 64,920

Claims priority, application Great Britain Oct. 26, 1960

Term of patent 14 years

(Cl. D26—14)

FIG. 1.

FIG. 2.

FIG. 3.

FIG. 4.

FIG. 5.

FIG. 6.

FIG. 1 is a front perspective view from above of a radar reflector embodying our design;

FIG. 2 is a rear perspective view from below of said reflector;

FIG. 3 is a bottom plan view of the reflector;

FIG. 4 is a top plan view of the reflector;

FIG. 5 is a front elevational view of the reflector; and

FIG. 6 is a side elevational view of the reflector.

The dominant feature of our design resides in the combination, on the radar reflector disclosed having two ninety degree intersecting vertical planes, of the two opposed vane-like elements affixed to the bottom of the square covering plate and extending outwardly therefrom in opposed relationship, all as shown.

We claim:

The ornamental design for a radar reflector, as shown and described.
